RESILIENT GOLF CLUB HEAD

Leonard A. Young, Detroit, Mich.

Application December 31, 1931, Serial No. 584,264

7 Claims. (Cl. 273—78)

My invention relates to golf clubs and more particularly to an improved golf club head.

An object of the invention is to provide a golf club head which is so constructed as to have a cushioning effect and tend to absorb the shock or vibrations incident to the club head striking the ball.

Further the invention provides a golf club head wherein the contact or striking face of the club is provided with resilient elements which present a surface to which the ball will adhere, more or less, and not slip thereon, producing somewhat of a gripping action on the ball, whereby a back spin may be given the ball when struck, if so desired.

The invention also provides a golf club head embodying a shell and a precast insert or weight block which is united to the shell through the medium of a substance of limited resilience which may be vulcanized or otherwise caused to adhere to and unite said shell and block, said substance, because of its resilience, serving as a cushioning medium to dampen vibrations which would otherwise be transmitted from the head to the club shaft, and thence to the hands and arms of the player.

With the above and other ends in view the invention consists in the novel combination of elements and constructions and arrangements of parts, all as hereinafter set forth and more particularly pointed out in the appended claims, reference being had to the accompanying drawing in which

Fig. 1 is a front elevation of a golf club illustrative of an embodiment of the present invention;

Fig. 2 is a similar view showing the side of the club opposite that shown in Fig. 1;

Fig. 3 is a transverse section of the club head, substantially upon the line 3—3 Fig. 1;

Fig. 4 is a longitudinal section through the same upon the line 4—4 Fig. 1;

Fig. 5 is a front elevation illustrative of a modified construction;

Fig. 6 is a similar view showing the side of the club opposite that shown in Fig. 5;

Fig. 7 is a transverse section of the club head substantially upon the line 7—7 Fig. 5; and

Fig. 8 is a longitudinal section through the same upon the line 8—8 Fig. 5.

Referring to the invention in detail, and particularly to that embodiment disclosed in Figs. 1—4 inclusive, a shell 5 which is substantially concavo-convex in cross section, has offset edge channel portions 6 extending along the upper

and lower edges of the shell and a similar offset channel 10 extending along the end edge of the shell. The smaller end of this shell is formed with an integral angularly extending tubular member or hosel 7 to receive the lower end of the usual shaft 8.

Fitting within the shell 5 is a precast body 11 adapted to add weight to the club head and which body or block is formed with a convex rear surface 12 fitting within the concavity of the shell 5 and having laterally extending ribs or edge portions 13 lying within the offset channels 6 and a similar extended rib or projection 14 lies within the offset channel 10 at the end of the shell. The front or ball engaging face of the body or block 11 is substantially flat and flush with the front edges of the shell.

For the purpose of dampening the vibration or absorbing the shock incident to the body 11 contacting with the ball, a sheet or coating of rubber 16 is interposed between the inner surface of the shell and the rear surface of the body 11, and is also extended into the edge channels 6 and 10, and as shown in Fig. 4 this rubber sheet or coating 16 is extended rearwardly between the lower end portion of the staff 8 and the adjacent rear end of the body 11. In addition to this rubber coating serving as a shock absorbing medium or cushioning element for the club head, it also serves as a union between the body 11 and shell, by being vulcanized or otherwise made fast directly to the inner surface of the shell and the opposed surface of the body 11, also within said edge channel of the shell.

For the purpose of further cushioning the club head and to cause the ball to back spin in flight when struck by the flat or striking face 15 of the block or body, said face is provided with rows of depressions 17, and received in each of these depressions and vulcanized or otherwise permanently secured within each of said depressions, is a rubber body, disk or button 18, the front face of each of which is flush with the striking surface 15 of the club head. It will thus be seen that these rubber inserts 18 will serve to cushion the blow, and at the same time will present a surface upon which the ball will not slip when struck and which by its gripping effect on the ball, will impart a back spin to the ball by a proper manipulation of the club.

By interposing the comparatively thin sheet of rubber 16 or other resilient material between the interior surfaces of the shell 5 and the exterior surfaces of the body 11, the full force of the blow incident to the face of this body or block striking

- a ball, and vibrations set up thereby will not be transmitted to the shell and consequently the shaft and handle of the club and thence to the hands and arms of the player, but will be absorbed to a maximum degree. Also, as heretofore stated, this thickness of elastic substance is vulcanized directly to the shell and body, thereby effectively uniting the same and holding the body firmly within the shell.
- 10 In the modification disclosed in Figs. 5 to 8 inclusive, the shell is formed with a front wall 19 and parallel upper and lower edge channels 20 and an end edge channel 21 forming a continuation of the channels 20. The filler or weight body 11a in this instance is formed with straight front side to seat toward the wall 19 of the shell and with a convex rear side forming the back face of the club head and is also formed with edge ribs or extensions 22 which engage within the channels 20 and also with an end rib or projection 23 which is engaged within the end channel 21.
- 15 The front wall 19 of the shell, in this embodiment of the invention, provides a striking surface for the club head and this front wall is provided with rows of depressions or countersinks 24 to receive resilient bodies or buttons 25 which are vulcanized or otherwise secured therein, the same corresponding to the buttons 18 and are for the same purpose. The face of the body 20 adjacent the wall 19 is provided with depressions 26 opposite the depressions 24 to receive the same, and interposed between the inner face of the front wall 19 and this front face of the body 11a, is a layer of elastic material 27 which is vulcanized or otherwise secured directly to the opposed faces of the shell and body. As shown particularly in Figs. 7 and 8, the depressions 24 and 26 provide a sinuous surface throughout substantially the entire area of the front wall 19 or face of the club head and these depressions are filled flush with the striking face of the club head, by the buttons 25. An effective bond is secured between this wall 19 and opposed face of the weight body 11a by means of the vulcanizing 25 of the layer 27 of rubber thereto, this rubber coating also extending between the buttons of the depressions 26 and the depressions 24 of the wall 19. Further the depressions 24 interfitting with the depressions 26, produce an effective union between the shell and body throughout the head face thus providing a materially greater area of connected surfaces than if the two surfaces were relatively flat, and movement of the wall 19 relative to the body face or springing away therefrom is prevented.
- 30 In this form of the invention the front or striking face of the club head is comparatively resilient and cushions the blow, absorbing the vibrations set up thereby rather than transmitting the same through the body 11 as in the case of the construction illustrated in Figs. 1 to 4. Further the weight member of the club head in the construction shown in Figs. 1 to 4, is resiliently mounted and the force of the swing of the club 35 is transmitted to said member through the interposed resilient covering at the rear of the weight, thus giving the maximum flight to the ball. In both embodiments of the invention, maximum flight is obtained, back spin is secured when desired, and vibrations incident to the blow are effectively damped out before they reach the hands of the player.

What I claim is:—

1. In a golf club head, a shell having channel portions extending along its side edges and end edge, and a weight body constituting the principal mass of the head and having marginal portions 80 extending within said channel portions of said shell with a rear flange of said channel engaged over said marginal portions to lock said body within said shell with the rear portion of said body projecting from said shell.
2. In a golf club head, a shell having a substantially flat front wall and a channel extending along the marginal edges of said wall, a weight body constituting the principal mass of the head and having marginal portions to engage within 90 said channel with a rear flange of said channel engaged over said marginal portions to lock said body within said shell with the rear portion of said body projecting from said shell, and a thickness of yieldable material between the opposed faces of said shell and body.
3. In a golf club head, a shell having a front wall, a weight body in said shell, a thickness of yieldable material between the opposed faces of 100 said shell and body, said front wall of said shell having depressions therein, and yieldable elements secured within said depressions.
4. In a golf club head, a shell having a front wall provided with depressions, yieldable elements secured within said depressions, a weight body 105 within said shell and having its front face opposed to said front wall and formed with depressions to receive said depressions in said front wall of said shell, and a thickness of yieldable material between said front wall and body.
5. In a golf club head, a shell having a front wall provided with depressions, yieldable elements within said depressions in said front wall and secured therein, a weight body in said shell and having its front face opposed to said front 115 wall, and a thickness of yieldable material between said front wall and body, such yieldable material being intimately united to the opposed surfaces of said body and front wall.
6. A golf club including a head comprising a 120 solid weight body constituting the principal mass of the head, and having a substantially flat forward side and edge ribs increasing the width of said flat side, and having a convex rear side, a thin sheet metal shell having a wall covering said 125 flat side of said body and formed with a plurality of spaced apart depressions; and a resilient member in each of said depressions each having a flat face substantially flush with the flat striking face of the wall of said shell, to yield upon contact with 130 a ball and impart spinning motion thereto.
7. A golf club including a head comprising a solid weight body constituting the principal mass of the head and formed with a substantially flat forward side, a sheet metal shell having a wall 135 covering said flat side of said body and formed with a plurality of depressions, said shell being formed at one end to receive the end of a shaft, a layer of resilient material interposed between said wall of said shell and said flat side of said 140 body, and a plurality of spaced apart resilient members secured in said depressions in said wall of said shell and each having a flat face substantially flush with the flat striking face of said wall. to yield upon contact with a ball and impart spin- 145 motion thereto.

LEONARD A. YOUNG.
